UNITED STATES PATENT OFFICE.

CHARLES JAMES FOX, OF LONDON, ENGLAND.

AUTOMATIC FIRE-ALARM SYSTEM.

No. 903,076.

Specification of Letters Patent.

Patented Nov. 3, 1908.

Application filed April 3, 1906. Serial No. 309,603.

To all whom it may concern:

Be it known that I, CHARLES JAMES FOX, a subject of the King of Great Britain, and resident of 11 Queen Street Place, in the city 5 of London, England, lieutenant-colonel, have invented an Automatic Fire-Alarm System, of which the following is a specification.

This invention consists of a combined electric bell service and automatic fire alarm system; that is to say, a system in which the leads for the electric bell installation serve also as leads for the fire alarm thermostat circuit, so that the leads appertaining to the thermostat in any apartment will be tested 15 each time the electric bell in said apartment is used.

The invention also comprises a special construction of thermostat for use in said system.

20 The invention will be described with reference to the accompanying diagram which illustrates a typical example of the application of the invention to the electric bell service and fire alarm installations appertaining 25 to a single apartment, the ordinary bell-push leads, and the additional leads connecting with the thermostat, being shown by thin and thick lines respectively.

A represents the ordinary service bell push 30 in the apartment; B and C the corresponding bell and indicator respectively; D the fire alarm thermostat in the apartment; E the fire alarm push (preferably of the "break the glass" type) which may be, say, in a corridor 35 or other publicly accessible place adjoining the apartment; F and G the fire alarm bell and indicator respectively (which may be, say, in a fire brigade station); and H the battery supplying current to the entire system. 40 Obviously however there might be separate batteries at the building containing the apartment and at the station respectively.

According to the present invention the terminal contacts a^1 a^2 of the ordinary service bell push A in any apartment are connected to the respective members of the battery, bell and indicator circuit, not directly as has been usual heretofore, but through the respective terminals d^1 d^2 of a thermostat circuit closer D situated in the apartment. To enable this to be done while retaining the existing leads 1, 2 from the service bell push

terminals a^1 a^2 , these leads are disconnected close to the push as indicated by the dotted lines, and a wire is led from each terminal 55 contact of the push to one of the thermostat terminals and back to the neighborhood of the push where the wire is then connected to that member of the battery, bell and indicator circuit to which the corresponding terminal 60 contact of the push had previously been directly connected.

The thermostat which it is preferred to employ is of a so-called "three-way" type having independent automatic circuit closers 65 adapted to come into action at the same or at different temperatures as may be arranged; the circuit closers (say two) having a common return wire which constitutes one member of the combined service bell push and 70 alarm circuit above mentioned, while of the other leads controlled by the respective circuit closers, one constitutes the second member of the same combined service bell push and alarm circuit and another constitutes 75 the corresponding member of a "corridor" alarm circuit having the same common return. By this arrangement, an alarm of fire in any apartment will be automatically notified both by the service and corridor (or fire 80 station) bells and indicators as hereafter explained.

According to the preferred construction the thermostat instrument D comprises a metal base or frame d connected to the common return wire, and two independent horizontal strips J, K of metal each secured between fixed points on the base or frame so that the strip when expanded by heat will sag downwards from its normal position and, upon the rise of temperature producing a predetermined deflection of the strip, the latter will come into contact with a stop formed by an electrical terminal in circuit with the corresponding member of the automatic 95 alarm circuit, this circuit being consequently closed and the alarm given.

The terminal constituting the stop in the case of each strip consists of a set screw carried by, but insulated from, the metal base of the instrument, and capable of being adjusted relatively to the level of the strip for the purpose of determining the amount of deflection and consequently the degree of

temperature at which the alarm circuit shall be closed, means being provided for locking the set screw in the position at which it has been set.

- 5 In the example illustrated the base d of the thermostat D has two terminals d^1, j whereof d^1 is connected by a wire 3 with the terminal a^1 of the service bell push A, while j is connected by a wire 4 with the wire 1 which, 10 although originally coupled to the terminal a^1 , has been disconnected therefrom as already mentioned. The wire 1 is coupled to one terminal of the service indicator C whose other terminal is connected by the wires 5, 6 15 with one pole of the battery H whereof the other pole is connected by the wire 7 with one terminal of the service bell B. The other terminal of this bell is connected to the wire 2 which, although originally coupled to the terminal a^2 of the service bell push A, has 20 been disconnected therefrom as already mentioned, the terminal a^2 and the wire 2 being now independently connected by the wires 8 and 9 respectively, with the adjustable screw 25 terminal d^2 of the thermostat D, whereof the flexible metal strip J is adapted, on being expanded by a predetermined increase of temperature within the apartment, to sag down and make electrical contact with the terminal d^2 .

In consequence of the arrangement above described, every time the service bell push A is operated, the current whereby the service bell B is rung and the service indicator C is 35 actuated will pass through the entire length of the thermostat leads appertaining to the bell push A, the current passing (in the example illustrated) from the battery H by way of wire 7 to the bell B, thence by wires 2 40 and 9 to the thermostat adjustable terminal d^2 , thence by wire 8, terminal a^2 , service push A, terminal a^1 , wire 3, thermostat terminal d^1 , base d , terminal j , wire 4, the service indicator C, and wires 5 and 6 back to the battery H. By this means there is afforded, at 45 every actuation of the service bell push A, a test as to the whole system of wiring through which, on the thermostat strip J coming into action in case of fire, an alarm would be conveyed to those within the building where the apartment is situated. Such an alarm would of course be sounded by the service bell B and visually notified by the service indicator C appertaining to the apartment in 55 question, but automatically, and altogether independently of the actuation of the service bell push A, the current passing in this case from the battery H by way of wire 7 to the bell B, thence by wires 2 and 9 to the thermostat adjustable terminal d^2 , thence by strip J, thermostat base d , terminal j , wire 4, indicator C, and wires 5 and 6 back to the battery H.

The flexible metal strip K of the thermostat D is adapted on being expanded by a predetermined increase of temperature, to sag down and make electrical contact with the adjustable screw terminal k , whereof the construction is similar to that of the adjustable terminal d^2 already referred to. This 70 adjustable terminal k is connected by the wire 10 with the terminal e^1 of the corridor or other fire-alarm push E which is also connected by wire 11 to one terminal of the fire station (or other) indicator G whose other terminal is connected by wire 12, through the fire station bell or other alarm apparatus F and wire 13, with the wire 7 which leads to one pole of the battery H. The other terminal e^2 of the corridor push E is connected by 80 wire 14 with the wire 6 which leads to the opposite pole of the battery.

When the corridor push E is actuated, current passes from the battery H by wires 7 and 13, station bell F, wire 12, station indicator G, wire 11, terminal e^1 , push E, terminal e^2 , and wires 14 and 6 back to the battery H. Should a fire occur in the apartment however, on the predetermined temperature being attained the strip K by sagging 90 down so as to make contact with the adjustable terminal k will close the circuit through the bell F and indicator G independently of the actuation of the push E, the current then passing from the battery H through wires 7 and 13, bell F, wire 12, indicator G, wire 11 95 terminal e^1 , wire 10, terminal k , strip K, thermostat base d , terminal j , wires 4 and 1, indicator C, and wires 5 and 6 back to battery H. 100

Claims.

1. A combined service electric bell system, and automatic electric fire alarm system, consisting in combination with a service electric bell circuit, of a thermostat whose normally separated elements are permanently in series with the respective members of said bell circuit, so that the sounding of the service bell when said circuit is operated will indicate that the current has passed through the circuit of the said thermostat elements, as specified. 105

2. An automatic electric fire-alarm system comprising a service electric bell circuit, a thermostat circuit, and a corridor electric bell circuit, the thermostat being provided with a common return wire for all the circuits, and other leads controlled by the service and corridor circuit closers, so that the respective bells may be operated independently of each other by the respective circuit closers or concurrently by the thermostat substantially as specified. 115

3. An automatic fire alarm system comprising a thermostat having a plurality of circuit closers adapted to be actuated at dif- 120 125

ferent temperatures, a service bell circuit adapted to be operated by one of the circuit closers of the thermostat, means for operating the service bell circuit independent of the 5 thermostat, a corridor bell circuit adapted to be operated by the other circuit closer of the thermostat, and means for operating the corridor bell circuit independently of the thermostat.
